UNITED STATES PATENT OFFICE.

JOHN J. QUINLAN, OF BOSTON, MASSACHUSETTS, ASSIGNOR TO UNITED STATES MANUFACTURING COMPANY, A CORPORATION OF MAINE.

WRENCH.

SPECIFICATION forming part of Letters Patent No. 728,410, dated May 19, 1903.

Application filed January 19, 1903. Serial No. 139,643. (No model.)

To all whom it may concern:

Be it known that I, JOHN J. QUINLAN, a citizen of the United States, residing at Boston, in the county of Suffolk and State of Massachusetts, have invented certain new and useful Improvements in Wrenches; and I do hereby declare the following to be a full, clear, and exact description of the invention, such as will enable others skilled in the art to which it appertains to make and use the same.

This invention relates to wrenches; and it consists in the novel construction and combination of the parts hereinafter fully described and claimed.

15 In the drawings, Figure 1 is a front view of the wrench with the handle cover-plate removed. Fig. 2 is a side view of the wrench.

A is the handle of the wrench, which is secured to the shank B, which has a stationary jaw b at its end.

20 C is a slidable jaw provided with sockets c, which slide on the shank B.

D is a serrated locking-bar, which is pivoted to the jaw C by a pin d, but which may

25 be secured to it rigidly, if desired. This bar D slides in a chamber E inside the handle along the shank B. The side wall e of the chamber E forms an abutment for the bar D.

30 F is a retractable toothed rack or bar arranged in a chamber f in the shank B opposite the bar D. The rack or bar F is normally held out of engagement with the bar D by means of springs G, arranged between the lugs g at the ends of the chamber f and

35 lugs g' at the ends of the rack.

H represents guide-pins for the rack. The lugs g' have holes which slide over the guide-pins, and the guide-pins pass through the lugs g and through the springs and are secured in any approved manner.

40 I is a cam-wheel arranged at the back of the rack in a notch i in the shank, with its periphery projecting through slots in the handle and in its cover-plate a'. The cover-plate a' may be dispensed with altogether, if desired, or it may be formed integral with the handle. The cam-wheel is provided with a shaft i', which is journaled in a hole in the shank B. When the cam-wheel is partially

45 revolved from the position shown in Fig. 1 by means of the thumb and fingers, it presses the rack into engagement with the serrated locking-bar D and grips the locking-bar

against the abutment e, so that the slidable jaw C is locked to the shank and cannot be 55 slid longitudinally. When the locking-bar is released from the retractable bar F by the action of the springs or by being retracted in any other approved manner, the slidable jaw may be slid on the shank to any desired position. The slidable jaw may be slid by grasping it or one of its sockets between the thumb and fingers, or a peg j may be connected to the locking-bar and arranged to slide in a slot j' in the handle. When the peg is used, 60 the wrench can be operated altogether with one hand, which is sometimes convenient.

What I claim is—

1. In a wrench, the combination, with a shank having a jaw, and a handle provided 70 with an abutment; of a jaw slidable on the said shank, a locking-bar pivoted at one end to the said slidable jaw and arranged between the said shank and abutment, a retractable bar for engaging with the said locking-bar, and means for operating the said retractable bar, substantially as set forth.

2. In a wrench, the combination, with a shank having a jaw, and a handle provided with an abutment; of a jaw slidable on the 80 said shank and provided with a locking-bar which slides between the said shank and abutment, a retractable bar for engaging with the said shank, springs for retracting the said bar, and a revoluble cam operating to press 85 the said bar into engagement with the said locking-bar, substantially as set forth.

3. In a wrench, the combination, with a shank having a jaw and having also a chamber provided with lugs at its ends, and a handle provided with an abutment opposite said chamber; of a jaw slidable on the said shank and provided with a locking-bar which slides between the said shank and abutment, a retractable bar arranged in said chamber and having lugs at its ends opposite the aforesaid lugs, retracting-springs arranged between the opposed lugs, and means for pressing the said bar into engagement with the said locking-bar, substantially as set forth.

100 In testimony whereof I affix my signature in presence of two witnesses.

JOHN J. QUINLAN.
